Primary Examiner — Catherine Ho

(57) **CLAIM**

The ornamental design for a label, as shown and described.

DESCRIPTION

The file of this patent contains at least one drawing/photograph executed in color. Copies of this patent with color drawing(s)/photograph(s) will be provided by the Office upon request and payment of the necessary fee.

1. Label

2. Label

1. Front view of the first embodiment for a label, showing my new design.

2. Front view of the second embodiment for a label, showing my new design.

The dot-dash broken lines in the reproductions define the bounds of the claimed design and form no part thereof.

1 Claim, 2 Drawing Sheets
(2 of 2 Drawing Sheet(s) Filed in Color)
